ELECTRIC FENCE CHARGER

Glen Everett Borton, Munson, Mich.

Application October 19, 1938, Serial No. 235,919

2 Claims. (Cl. 256—10)

My invention relates generally to means for charging a one-wire electric fence, and particularly to automatic electric fence controlling means which maintains the fence in an energized condition, and an important object of my invention is to provide an arrangement of this character which affords no injury to animal or human life, and whose current consumption is practically negligible despite the fact that the fence is kept in constantly effective shocking condition.

Other important objects and advantages of my invention will be apparent from a reading of the following description taken in connection with the drawings, wherein for purposes of illustration I have shown a preferred embodiment of my invention.

In the drawings:

Figure 1 is a general schematic wiring diagram showing the electrical components and the connections therebetween.

Figure 2 is an enlarged longitudinal vertical sectional view taken through the rotary contact drum.

Figure 3 is a transverse vertical sectional view taken through Figure 2.

Figure 4 is an end elevational view of the self-starting low watt A. C. motor and showing the reducing gears which drive the rotary contact drum.

Referring in detail to the drawings, and particularly to Figure 1 thereof, the numerals 5 and 6 refer respectively to the sides of a preferably 110 volts A. C. current input. The wire 5 is connected by a branch 7 with one side of the small self-starting low watt rating motor 8 on whose shaft is a small pinion 9 which is in mesh with an idler pinion 10 which is in turn in mesh with a gear 11 which is fastened to the shaft 12 which turns in the respective supports 13 and 14 and has fixed thereon the contact drum 15.

The contact drum 15 comprises a dielectric cylinder 16 on which are circumposed the longitudinally spaced cylindrical segments 17 and 18 which are separated by a slot 19 which at diametrically opposite points of the drum has longitudinally extending U-shaped portions, said slot and its said portions being filled with insulation as indicated by the respective numerals 19' and 20', whereby the segments 17 and 18 are insulated from each other. Two contact fingers 21 and 22, respectively, defined on the segment 18 by the U-shaped portions extend into the segment 17 as clearly shown in Figure 1. A first brush 23 constantly engages that por-

tion of the segment 17 which lies to the left of the fingers 21 and 22, so that the brush 23 is in uninterrupted electrical engagement with the segment 17. A second brush 24 is positioned to engage the segment 17 and the fingers 21 and 22, the insulation in the slots 19 and 20 causing a disconnection electrically of the brush 24 with the segment 17 twice each full revolution of the drum. A third brush 25 engages that portion 10 of the segment 18 which lies to the right of the fingers 21 and 22, and is in uninterrupted electrical engagement with the segment 18. A wire 26 leads from the third brush 25 to the single wire fence 27.

15 The first brush 23 is connected to one side of the secondary 28 of the radio transformer 29, and a branch 30 is grounded as indicated by the numeral 31 and located between the brush 23 and the said side of the secondary 28. The remaining side of the secondary 28 is connected by a wire 32 to the second brush 24.

20 The primary 33 of the transformer 29 has one side connected to the alternating current input wire 5, while the remaining side of the primary 33 is connected to one end of the winding 34 of a relay coil 35, the remaining end of this winding 34 being connected by a wire 36 to the arm 37 of a variable rheostat which is generally designated 38.

25 The resistance element 40 of the rheostat 38 is connected to the alternating current input wire 6 through the medium of a fuse 41. A wire 42 connects with the wire 6 between the fuse 41 and the resistance element 40 of the rheostat and with the armature 43 of the relay which is generally designated 44, the armature being conductive in character and being opposed to a contact 45 from which is normally disengaged.

30 When the fence 27 and the ground 31 are connected through the body of an animal touching the fence, the circuit through the transformer secondary 28 is closed through the wire 26, brush 25, the drum segment 18, the brush 24, the wire 32. The increased load on the secondary causes an increase in the current flowing in the transformer primary 33 and in the relay winding 34, sufficient to cause the relay points 44 to close. This condition energizes the motor 8 from the alternating current lines 5 and 6, thereby starting the motor 8 and turning the drum 15 so that the segment finger 21 and the segment 17 exchange places in engagement with the brush 24, the latter continuing to maintain closed the circuit through the transformer secondary 28 until 35 the drum 14 turns to the position in which the

brush 24 engages the finger 22, when the motor 8 will be deenergized, unless the shorted condition of the fence remains.

Although I have shown and described herein a preferred embodiment of my invention, it is to be definitely understood that I do not desire to limit the application of the invention thereto, and any change or changes may be made in the structure and arrangement of the parts, within the spirit of the invention and the scope of the 10 subjoined claims.

Having described the invention, what is claimed as new is:

1. In combination, a source of alternating current, a self-starting electric motor having one side directly connected with one side of said source, a dual segment insulated contact drum operated by said motor, a pair of brushes constantly engaging the surface of the drum and severally engageable with said segments, a third brush arranged to engage with either of said segments in certain different positions of rotation of said drum, said third brush being arranged to be out of contact with both of said segments in other positions of rotation of said drum, means to connect one of said pair of brushes to an object to be charged, a high tension transformer having one side of its secondary connected to said third brush and having its remaining side connected to the remaining brush of said pair, and grounded, the primary of said transformer having one side thereof directly connected to the same side of said source as said one side of the electric motor, a relay contact to which the remaining side of the said motor is connected, a conductive relay armature related to but normally disengaged from said relay contact, a relay coil in effective relation to said relay armature, said relay coil being balanced in ohmage with respect to the transformer primary, said armature being connected to the remaining side of said source, said relay coil having one end of its winding connected to the remaining side of the primary of the transformer and its other side connected to the said remaining side of said 45 source.
2. In combination, a source of alternating current, a self-starting electric motor having one side directly connected with one side of said source, a dual segment insulated contact drum 5 operated by said motor, a pair of brushes constantly engaging the surface of the drum and severally engageable with said segments, a third brush arranged to engage with either of said segments in certain different positions of rotation of said drum, said third brush being arranged to be out of contact with both of said segments in other positions of rotation of said drum, means to connect one of said pair of brushes to an object to be charged, a high tension transformer having one side thereof directly connected to the same side of said source as said one side of the electric motor, a relay contact to which the remaining side of the said motor is connected, a conductive relay armature related to but normally disengaged from said relay contact, a relay coil in effective relation to said relay armature, said relay coil being balanced in ohmage with respect to the transformer primary, said armature being connected to the remaining side of said source, said relay coil having one end of its winding connected to the remaining side of the primary of the transformer and its other side connected to the said remaining side of said 20 source, whereby establishment of a connection between said object and ground reduces the choke action of the primary of the transformer with respect to the relay coil, so as to permit said relay coil to be sufficiently energized to operate said armature and close the relay contacts so as to energize the primary of the transformer and charge said object with high tension current while operating said motor to cause intermittent interruption to the charging of said object.

GLEN EVERETT BORTON.
